CLAIM

The ornamental design for a portable telephone device, as shown and described.

DESCRIPTION

FIG. 1 is a front, top and right side perspective view of a portable telephone device, showing our new design;

FIG. 2 is a rear, bottom and left side perspective view thereof; and,

FIG. 3 is a front, top and right side perspective view thereof, with a camera extended.

The portions of the article not shown in the drawing or described in the specification form no part of the claimed design.
